UNITED STATES PATENT OFFICE

1,965,631

COATING APPARATUS

John E. Disch, Dolgeville, N. Y., assignor to
United Shoe Machinery Corporation, Paterson,
N. J., a corporation of New Jersey

Application December 29, 1931, Serial No. 583,695

8 Claims. (Cl. 91—39)

My invention relates to apparatus for coating such articles as parts of shoes, examples of the work for which the organization is well adapted being furnished by outsoles, insoles, the edges of uppers and the bottoms of lasted uppers, which are to receive an application of cement or other coating substance over certain areas.

The invention has as an object the provision of a conveniently arranged apparatus, which may be operated with facility, which will insure a regular flow of the coating substance to the work and which may unfailingly be kept in proper operating condition. For the attainment of this object, the apparatus illustrated as constituting one embodiment of my invention has a novel arrangement of receptacle for a coating substance and driven means for effecting delivery of the coating substance therefrom and for applying said substance to the work, together with improved means for controlling the delivery of the coating substance and for guarding against clogging of the applying means and the means delivering thereto.

In the accompanying drawing,

Fig. 1 represents my improved apparatus in perspective, parts being broken away;

Fig. 2 is a side elevation of the receptacle and more closely associated elements, parts being in section; and

Figs. 3 and 4 show applying nozzles adapted for operation upon articles differing from those for which the nozzle of Fig. 1 is most advantageously employed.

Standing upon legs 10, and conveniently cast in one piece, is a receptacle 12 divided by a vertical partition 14 into two compartments 16 and 18, these respectively furnishing containers for such substances as cement and a solvent for said cement. The compartment 18 is preferably of relatively small capacity. A cover 20 may normally close the receptacle, it being retained in place by a spring-catch 22. Lying transversely of the bottom of the receptacle is an elongated boss 24 having extending horizontally through it a cylindrical passage 26. Into this passage 26, an opening 28 of considerable diameter leads from the compartment 16, while a relatively contracted opening 30 connects the compartment 18 with the passage. Fitting in and extending through the passage 26 is a sleeve 32 held against longitudinal displacement at the inner end by a nut 34 and at the opposite end by a handle 36 fast upon it. This sleeve serves as a valve, having through it openings 38 and 40 preferably oppositely placed and arranged to be respectively brought into registration with the openings 28

and 30. This allows a flow into the sleeve from either the compartment 16 or the compartment 18. A stop-projection 42 is shown upon the handle 36, which may, by its contact with the bottom of the receptacle at opposite sides of the sleeve 32, determine the registration of either sleeve-opening with the corresponding compartment-opening. The delivery-passage within the valve-sleeve is continued by a flexible tube 44 having at its opposite extremity a cement-applying device or nozzle A (Fig. 1) arranged for manipulation by the operator. To prevent interference with the rotation of the valve-sleeve and with movement of the nozzle, connection to the tube at both ends may be through swivel-joints 46. The nozzle A appears as consisting of a tube 48, which may be surrounded by a yieldable sleeve 50 to furnish a better hold for the operator. At the delivery-end, this tube 48 may be curved to one side, to more conveniently direct the discharge, and is surrounded by a brush 52, by which the applied coating is distributed over the work, this work consisting, for example, of soles, the margins of which are to be coated. Fig. 3 shows another form B of applying nozzle. Here, the discharge is directly upon the work-surface, without spreading effect. The nozzle B is useful for the delivery of a comparatively thick coating of cement over the bottoms of lasted shoes in preparation for the attachment of the outsoles. A flange 54, fixed upon the tube at a chosen distance from the delivery-opening, furnishes a gage-surface, which, by contact with the work, will locate correctly the applied band of adhesive. Another nozzle (Fig. 4) may have a straight tube 56 with an outlet-slot 58 in its side at or near the otherwise closed end. This serves for applying a coating between connected parts, as shoe-uppers and their linings.

Situated within the valve-sleeve 32 beneath the openings 28 and 30, and extending therefrom through the tube 44 into the attached nozzle in proximity to the delivery-opening, is a feeding member for the cement, this member being preferably a flexible helix 60 of spring-wire having a diameter approaching that of the interior of the delivery-conduit. In the inner portion of the sleeve 32, the helix is connected to a flexible coupling member 62 secured at its opposite extremity to the shaft of an electric motor 64, the speed of rotation of which may be governed by a rheostat 66. The motor may be carried by a mounting 68 attached to the rear of the receptacle, with its shaft axially aligned with the sleeve.

While, obviously, any fluid substance may be

- delivered from either portion of the receptacle 12 exclusive of the other through the valve-sleeve 32 and connected tubing, I especially contemplate employing the container 16 for holding such a 5 cement as pyroxylin, with which work is to be coated, and the container 18 for a solvent for said cement, for example acetone, the latter being utilized for cleaning the cement-delivering connections. Consequently, in using the apparatus 10 in this manner, the valve-sleeve, during the coating operations, will be positioned as illustrated in Fig. 2. The circuit of the motor 64 being closed and the connected helix 60 being in rotation, cement will flow from the compartment 16 15 through the alined openings 28 and 38 into the valve-sleeve. Here it comes under the influence of the helix, the direction of rotation of which is such as to feed the cement continuously from the sleeve through the tube 44 and nozzle and out 20 of the delivery-opening of the latter upon the work. The nozzle and shoe-part operated upon are moved relatively to apply to said part an extended band over the desired area. The nozzle joined to the tube will be selected according to 25 the operation to be performed. The amount of cement applied and the time of delivery may be determined by the rotation of the motor, the contact-brush of the rheostat conveniently being shifted by a treadle (not shown). When the use 30 of the apparatus is to be discontinued, the handle 36 is turned to close the opening 28 from the cement-container 16 and bring the valve-opening 40 into registration with the opening 30 of the solvent-container. With the motor in operation, the 35 solvent will be forced through the valve-sleeve, the flexible tube and the connected nozzle, clearing the cement from the interior of the entire conduit and from the helix. Consequently, while the apparatus is at rest, there will be no cement to 40 harden and clog the delivery-connections, and operation may be resumed at once upon shifting the valve to the cement-delivering position. It will be seen that the arrangement of the motor, its connection to the helix and the location of the 45 valve give a compact arrangement, allowing uninterrupted access to the interior of the receptacle and providing for a connection of the flexible delivery-tube which facilitates manipulation by the operator of the delivery-nozzle.
- 50 Having described my invention, what I claim as new and desire to secure by Letters Patent of the United States is:
1. In a cementing apparatus, a receptacle having a partition dividing it into two containers, the 55 bottom of the receptacle having formed in it a cylindrical delivery-conduit connected to both containers, a valve-sleeve rotatable in the conduit and provided with openings communicating alternatively with said containers, a flexible tube 60 terminating in an applying nozzle and connected at its inner end to one end of said sleeve to receive the discharge through the sleeve, a flexible helix extending through said sleeve into said tube, and driving means for said helix connected thereto 65 through the other end of the valve sleeve.
  2. In a cementing apparatus, an applying device, a cement-container, a container for a solvent, connections between both containers and the applying device, a valve in the connections controlling the delivery from both containers, and a feeding member movable in the valve. 80
  3. In a cementing apparatus, an applying device, a cement-container, a container for a solvent, connections between both containers and the applying device, a valve movable in the connections to connect either one or the other of the containers to the applying device, and a helix rotatable in the valve. 85
  4. In a cementing apparatus, an applying device, a cement-container, a container for a solvent, connections between both containers and the applying device, a valve movable in the connections to connect either one or the other of the containers to the applying device, and a movable feeding member extending from the valve 90 through the connections to the applying device. 95
  5. In a cementing apparatus, a receptacle having a partition dividing it into two containers, a delivery-conduit connected to both containers, a valve-sleeve rotatable in the conduit and provided with an opening communicating with each container, an applying nozzle receiving the discharge through the delivery-conduit, and a helix rotatable in the valve-sleeve and delivery-conduit. 100
  6. In a coating-applying apparatus, a receptacle, a delivery conduit one side of which is connected to the receptacle, a sleeve valve controlling the passage from the receptacle to the conduit, a tube connected to receive coating material from one end of the conduit and provided with an applying device, a helix within said tube and extending at least partly within the sleeve valve, and means for driving said helix passing through the other end of said conduit. 105
  7. In a coating-applying apparatus, a receptacle, a delivery conduit one side of which is connected to said receptacle, a sleeve valve coaxial with the conduit and controlling the passage from said receptacle, a flexible tube the outer end of which is provided with an applying device and connected at its inner end to one end of said sleeve valve, a flexible helix extending through said sleeve valve and said tube, and driving means for said helix passing through the other end of said sleeve valve. 110
  8. In a cementing apparatus, a cement container, a container for a solvent, a conduit one side of which is connected to said containers, a sleeve valve within and coaxial with said conduit controlling the passage of cement and solvent to the conduit, a flexible tube having an applying device and connected to one end of said sleeve valve, a rotatable flexible feeding member extending through the tube and into the sleeve valve, and means for driving said feeding member extending into said sleeve valve. 115
  9. In a cementing apparatus, a cementing apparatus, a cement-container, a container for a solvent, a conduit one side of which is connected to said containers, a sleeve valve within and coaxial with said conduit controlling the passage of cement and solvent to the conduit, a flexible tube having an applying device and connected to one end of said sleeve valve, a rotatable flexible feeding member extending through the tube and into the sleeve valve, and means for driving said feeding member extending into said sleeve valve. 120
  10. In a cementing apparatus, a cement container, a container for a solvent, a conduit one side of which is connected to said containers, a sleeve valve within and coaxial with said conduit controlling the passage of cement and solvent to the conduit, a flexible tube having an applying device and connected to one end of said sleeve valve, a rotatable flexible feeding member extending through the tube and into the sleeve valve, and means for driving said feeding member extending into said sleeve valve. 125
  11. In a cementing apparatus, a cement container, a container for a solvent, a conduit one side of which is connected to said containers, a sleeve valve within and coaxial with said conduit controlling the passage of cement and solvent to the conduit, a flexible tube having an applying device and connected to one end of said sleeve valve, a rotatable flexible feeding member extending through the tube and into the sleeve valve, and means for driving said feeding member extending into said sleeve valve. 130
  12. In a cementing apparatus, a cement container, a container for a solvent, a conduit one side of which is connected to said containers, a sleeve valve within and coaxial with said conduit controlling the passage of cement and solvent to the conduit, a flexible tube having an applying device and connected to one end of said sleeve valve, a rotatable flexible feeding member extending through the tube and into the sleeve valve, and means for driving said feeding member extending into said sleeve valve. 135
